UNITED STATES PATENT OFFICE.

WILLIAM S. SEYMOUR, OF KENOSHA, WISCONSIN, ASSIGNOR TO ZALMON G. SIMMONS, OF SAME PLACE.

DESIGN FOR A FRAME FOR WIRE MATTRESSES.

SPECIFICATION forming part of Design No. 17,055, dated January 4, 1887.

Application filed October 22, 1886. Serial No. 216,982. Term of patent 14 years.

To all whom it may concern.

Be it known that I, WILLIAM S. SEYMOUR, of Kenosha, in the State of Wisconsin, have invented and produced a new and original 5 Design for Woven-Wire Mattress-Frames, of which the following is a specification, reference being had to the accompanying drawings, forming part thereof.

Figure 1 is an enlarged sectional perspective; Fig. 2, a plan view, and Fig. 3 a partial plan showing a modification.

The leading feature of my design consists in the frame having corresponding recesses or scallops in the edge of its ends, at the corners, 15 each scallop terminating with the end of the end rails. The edge of the end rails is fullest at the center, as shown in Fig. 2, and gradually recedes in contour from the center to the scallops, and the ends of the end rails are or- 20 namented by a plate the line of whose outer contour is beveled or curved at the end and joins the line of the adjacent surface of the scallops, the whole being designed to give the frame a better appearance.

A designates the side rails of the frame, and 25 B the end rails. C C C C are the recesses or scallops. D is the plate.

The end rails are fullest at e, and curved gradually inward as the outer line advances toward the scallops, giving the frame the appearance of being longest at the center, and the outer edges of the plates are beveled or curved inward.

What I claim, and desire to secure by Letters Patent, is—

The design for a frame for wire mattresses, 35 consisting of the parallel side rails, A A, and end rails, B B, having scallops C C C C in their outer edges, at the ends, forming a slight inward curve at the corners, substantially as 40 shown.

WILLIAM S. SEYMOUR.
